UNITED STATES PATENT OFFICE.

CHARLES W. SAMMONS, OF HIGHMORE, SOUTH DAKOTA.

AUTOMATIC BRAKE.

1,318,602.

Specification of Letters Patent. Patented Oct. 14, 1919.

Application filed June 6, 1918. Serial No. 238,536.

To all whom it may concern:

Be it known that I, CHARLES W. SAMMONS, a citizen of the United States, residing at Highmore, in the county of Hyde and State of South Dakota, have invented certain new and useful Improvements in Automatic Brakes, of which the following is a specification.

This invention relates to braking means, and more particularly to means for automatically braking wagons and similar vehicles.

One of the main objects of this invention is to provide a braking device of the character described, of simple construction and operation, which may be readily applied to a wagon or similar vehicle of standard construction.

A further object is to provide a braking mechanism which is connected to the tongue of a wagon in such manner as to cause the brake to be applied to the rear wheels of the vehicle when the draft animals are holding back on the tongue, such as when going down a hill or incline.

A still further object is to provide a braking mechanism of the character described in which the braking effect will increase in accordance with the holding back pressure exerted on the tongue and will be automatically released when the backward pressure on the tongue ceases.

Further objects will appear from the detailed description.

In the drawings:

Fig. 1, is an underneath view of a wagon gear of standard construction with a braking mechanism constructed in accordance with my invention applied.

Fig. 2, is a detail side view of the tongue used for controlling the braking mechanism.

Fig. 3, is a side view of a wagon gear with a modified form of the mechanism applied.

Fig. 4, is a section taken substantially on line 4-4 of Fig. 3.

Fig. 5, is a section taken substantially on line 5-5 of Fig. 3, the body portion of the tongue being shown in side perspective.

The wagon gear may be of any suitable or standard construction comprising the front axle "a," rear axle "b," reach "c," rear hound "d," front hound "e," and the fifth wheel

frame "f." The pole or tongue "g" is secured at its inner end, to the front hound in the usual manner. All of these members are of any suitable or standard construction, with the exception of the tongue which is of telescoping construction and controls the operation of the braking mechanism.

The tongue "g" is provided with a stub portion 1, which is secured between the front hounds "e." The front portion of this stub is reduced to form a neck 2, which fits snugly into a boxing or casing 3 secured on the forward member 4 of the tongue and projecting rearwardly therefrom. In this manner, the two sections of the tongue are telescopically connected so as to permit movement of the outer section 4 along the inner section or stub 1. An expansion coil spring 5 is mounted within the casing 3 between the members 2 and 4 and acts to normally hold these members distended. Complete withdrawal of casing 3 from the neck 2 of the stub is positively prevented by a bolt 6 inserted through the neck and through cooperating slots 7 provided in the side walls of the casing 3.

Casing 3 is provided with an integral rearwardly projecting bar 8 which fits snugly against the under face of the neck 2 and stub 1. This bar is slideable through a keeper strap 9 secured about the stub 1 adjacent the inner end thereof and is pivotally secured, at its inner end, to the outer ends 85 of two connecting links 10 and 11. Link 10 is pivotally secured, at its rearward end, to the inner end of a lever 12 which is pivotally mounted as at 13, on the front axle "a," the link 11 being pivotally secured at its 90 rearward end to the inner end of a similar lever 14 which is similarly mounted on the front axle. Lever 12 is pivotally connected, at its outer end, to one end of a draw bar 15 by means of a link 16, the lever 14 being 95 similarly connected to the other end of the draw bar by a link 17.

In using this mechanism, the draft animal will be connected to the forward end of the tongue "g" in the usual manner, so that, 100 when descending an incline, backward pressure will be exerted on the forward section 4 to move the same rearwardly. When this occurs, the inner ends of the levers 12 and

14 will be moved rearwardly so as to swing the outer ends thereof forwardly thus moving the draw bar 15 forwardly. This bar is connected by a link 21 and pull rod 18 to the forward ends of two links 19 and 20, the rearward ends of which are pivoted to the inner ends of two levers 22 and 23, respectively. These levers are pivotably mounted adjacent their outer ends, as at 24, on the rear axle "b," and the outer ends of the levers are pivotally connected by links 25 to a brake beam 26 which carries at each end a brake block 27 movable into engagement with the rear wheel 28 of the vehicle. When the draw bar 15 is moved forwardly, the levers 22 and 23 will be rocked about their pivots so as to cause rearward movement of the brake beam 26, thus bringing the blocks 27 into operative engagement with the wheels 28 so as to exert a braking effect thereon. The pressure which is exerted on the blocks 27 will vary directly with the rearward pressure exerted on the forward portion of the draw bar thus giving direct and automatic control of the braking mechanism. When the end of the incline down which the vehicle is moving is reached, and the vehicle moves on level ground, or up hill, the forward section 4 of the tongue "g" will be moved forwardly by means of the spring 5, thus returning the levers 12, 14 22 and 23 to their initial position and moving the brake blocks 27 out of engagement with the wheels 28.

When it is desired to back the vehicle, it is necessary to provide some means for preventing application of the brakes. For this purpose, a latch or locking hook 29 is hingedly mounted on the casing 3 adjacent the inner end thereof for movement about a pivot extending transversely of the casing. This hook is adapted to engage into a recess 30 in the neck 2 of the stub portion 1 of the pole. The two sections of the tongue will then be locked against relative movement, thus permitting the tongue to be used in the ordinary manner and preventing operation of the brakes. Normally, of course, the hook or latch member 29 will be turned forwardly into inoperative position so as to permit the brakes to be operated in the manner described.

In the form of the invention illustrated in Figs. 3 to 5 inclusive, the levers 12, 14, 22 and 23, draw bar 15 and associated parts have been replaced by an operating cable 31 which is passed over grooved pulleys 32 and 33 rotatably supported in brackets 34 and 35 mounted on the rear axle "b" and tongue "g" respectively. The forward end of this cable is secured to a rectangularly disposed finger 36 provided at the inner rearward end of the bar 8 of casing 3 of the pole or tongue, the rearward end of the cable being secured through an eye-bolt 37 in the brake

beam 26. In this form of the invention, as in the form illustrated in Figs. 1 and 2, when the forward portion of the tongue or pole "g" is moved rearwardly, the brakes will be automatically applied to the rear-wheels of the vehicle. Also, when the forward section is moved by the spring 5, the brakes will be automatically released.

While the invention is disclosed as applied to a vehicle adapted to be drawn by draft animals, it will be obvious that it can be used equally well with any vehicle which is drawn by suitable draft means, the tongue "g" being used for securing the vehicle to the means for drawing the same.

The foregoing description and the drawings have reference to what may be considered the preferred or approved form of invention. It is to be understood that I may make such changes in construction and arrangement and combination of parts, materials, dimensions, etc., as may prove expedient and fall within the scope of the appended claims.

Having thus described my invention what I claim as new and desire to secure by Letters Patent is:—

1. In combination with a vehicle including front and rear axles having supporting wheels, and a tongue including a rearwardly projecting bar; of braking means including a pair of spaced levers pivotally mounted upon each axle, links connecting the inner ends of the levers on the front axle to said bar, a draw bar having links at its outer end connected to the outer ends of the levers on the front axle, links pivotally connected to the inner ends of the levers on said rear axle, a link and pull rod connected to the last mentioned links and to said draw bar, and a brake beam having links connected adjacent the ends thereof to the outer ends of the links on the rear axle, whereby as said tongue moves said first mentioned bar rearwardly, said links and levers, draw bar and pull rod will also be moved so as to cause the brake beam to come into a binding engagement with the wheels of the rear axle, as and for the purposes set forth.

2. In combination with a vehicle running gear including a braking means, of a tongue consisting of a rear portion and a forward member, said rear portion comprising a stub having a reduced neck extending forwardly therefrom, a casing carried upon said forward member and fitting upon said neck, a spring interposed between said forward member and said neck within said casing, thus normally holding the portions distended, said casing having aligned slots communicating with an opening in said neck, a bolt passing through said slots, a hook pivoted upon said casing at the rear end thereof, said neck having a recess extending thereinto from its top portion, 130

whereby the hook may be swung into the recess to hold said casing from shifting along said neck, thus said head may be swung over to fit upon said casing to permit of the 5 casing moving upon the neck, and said tongue being connected to said running gear, said stub having a keeper strap thereon, a bar extended from the rear end of said casing and passing through said keeper strap

and being connected to said braking means, 10 as and for the purposes set forth.

In testimony whereof I affix my signature in presence of two witnesses.

CHARLES W. SAMMONS.
